CHILD'S RIDING TOY

Walter Hubiak, Erie, Pa., assignor to
Louis Marx & Co., Inc.

Filed June 20, 1969, Ser. No. 17,797

Term of patent 14 years

Int. Cl. D21—02

U.S. Cl. D34—15

FIG. 1

FIG. 2

FIG. 3

FIG. 4

FIG. 5

FIG. 1 is a front perspective view of a child's riding toy showing my new design;

FIG. 2 is a top plan view thereof;

FIG. 3 is a front view thereof;

FIG. 4 is a side elevation view thereof; and

FIG. 5 is a rear view thereof.

I claim:

The ornamental design for a child's riding toy, as shown.
